UNITED STATES PATENT OFFICE

118,301

DESIGN FOR AN ARM FOR LAMP FIXTURES

August O. Elting, Chicago, Ill.

Application October 9, 1939, Serial No. 87,589

Term of patent 14 years

To all whom it may concern:

Be it known that I, August O. Elting, a citizen of the United States, residing at Chicago, in the county of Cook and State of Illinois, have invented a new, original, and ornamental Design for an Arm for Lamp Fixtures of which the following is a specification, reference being had to the accompanying drawing, forming a part thereof, in which:

Fig. 1 is a plan view of the arm for lamp fixtures showing my new design.

Fig. 2 is a side elevational view.

Fig. 3 is an inverted plan view.

Fig. 4 is an end elevational view thereof.

I claim:

The ornamental design for an arm for lamp fixtures, as shown.

AUGUST O. ELTING.
